UNITED STATES PATENT OFFICE.

WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

ELECTRIC PUMP-GOVERNOR.

1,071,830.

Specification of Letters Patent.

Patented Sept. 2, 1913.

Application filed April 10, 1909. Serial No. 489,093.

To all whom it may concern:

Be it known that I, WALTER V. TURNER, a citizen of the United States, residing at Edgewood, in the county of Allegheny and State of Pennsylvania, have invented new and useful Improvements in Electric Pump-Governors, of which the following is a specification.

This invention relates to pressure governors, and more particularly to a pump governor of the type adapted for operating an electric switch, to control the circuit of an electric pump motor.

My invention is designed more especially to provide an improved electric pump governor capable of handling heavy currents and low voltages, such for instance, as met with in single phase electric installations.

One feature of my improvements contemplates the provision of means for effecting a quick snap-like cutting-in action of the switch, so as to prevent the formation of destructive arcs such as are otherwise liable to be produced when the switch contacts are brought together, especially where heavy currents and low voltages are employed.

Another object of my invention is to provide means for causing the place of contact between the contact members of the switch to be shifted from the portions of said contact members at first engaging, to other portions thereof, for the purpose of affording clean, smooth contact surfaces for the final contact, thereby obviating the tendency to form a poor connection at the switch, due to pitting or roughness of the contact finger ends caused by fusing or burning.

Another object of my invention is to provide means for maintaining a heavy pressure between the switch contact members, when in engagement, so as to improve the conductivity and effectiveness of the switch connection.

Another object of my invention is to provide a pump governor of generally improved construction.

Other features of importance will be referred to in the more detailed description of the invention.

In the accompanying drawing; Figure 1 is a vertical section of an electric pump governor embodying my improvements; Fig. 2 a fragmentary sectional view of a portion of the electric switch mechanism, partly broken away, to show the spring device for

the lower contact member; Fig. 3 a fragmentary elevational view of a portion of the switch mechanism, with the upper contact member removed; and Fig. 4 a view similar to Fig. 2, showing the relative position of the switch parts when the contacts are separated.

As illustrated in Fig. 1 of the drawing, the governor may comprise a casing 1 having a cylindrical chamber containing a piston 2 which divides the chamber into an upper chamber 3 and a lower chamber 4. The governor also comprises a valve casing 5 having a chamber containing a movable abutment provided with two piston heads 6 and 7 operating respectively in piston chambers 8 and 9. The valve chamber 10 intermediate the heads 6 and 7 contains a main slide valve 11 and an auxiliary slide valve 12, mounted on the main slide valve and having a movement relative thereto.

A high tension regulating device comprising a diaphragm 13, subject on one side to pump pressure and on the opposite side to the pressure of an adjustable spring 14, operates a release valve 15 for releasing air from the chamber 8 at the outer face of piston head 6; and a low pressure regulating device comprising a diaphragm 16 subject on one side to pump pressure and on the opposite side to the pressure of an adjustable spring 17 operates a valve 18 for releasing air from piston chamber 9 at the outer face of piston head 7.

According to my improvements, the switch piston 2 is provided with a central differential piston head 19 operating in a piston chamber 20. The piston chamber 4 communicates with a port 21, leading to the seat of the main valve 11 and piston chamber 20 communicates with a passage 22 having port openings 23 into the piston chamber 3. The chamber 3 is provided with an atmospheric port 24 and piston 2 is subject to the pressure of two springs 25 and 26 contained in the chamber 3 and tending to move said piston to its inner position.

Piston rod 27 of the piston 2 carries a pivotally mounted lever 28 upon its outer end, suitably insulated from the piston rod and having one end provided with a contact member 29, the opposite end thereof being slotted for a fulcrum pin 30 mounted in a suitable bracket 31.

The other contact member 32, of the

switch, is secured to a pivoted arm 33, mounted between standards 34 of a bracket 35, so as to have a vertical movement. A spring rod 36, subject to the pressure of a coil spring 37 is pivotally attached to the arm 33 and tends to force the arm and its contact in an upward direction. The rear of the arm 33 is provided with a stop 38 adapted to bear on a portion of the standards 34 and thereby limit the upward movement of the arm, the movement of the arm 33 in the opposite direction being limited by engagement of portion 61 with a fixed abutment 62.

15 The arm 33 and contact member 32 are suitably insulated from the main casing of the governor and a flexible conductor 39 connects said arm with the conductor cable 40.

20 A pneumatic blow out device for extinguishing or preventing the formation of arcs may be employed comprising a piston valve 42 controlling communication from a supply passage 43, leading to the seat of the main slide valve 11 to a blow out passage 44 having a nozzle 45 through which air may be directed to the contact members as they separate. One side of the piston valve 42 is subject to the pressure of a spring 47, and 25 is in communication with a passage 46 opening into the piston chamber 3; and the opposite face of said piston valve is subject to the pressure of air admitted to the supply passage 43.

30 In operation, there being no fluid pressure on the inner face of piston 2, the pressure exerted by the springs 25 and 26 holds the parts in their inner cut-in position, closing the pump motor circuit through the contact 35 members 29 and 32, as shown in Fig. 1. The pump motor then operates the pump to compress air into the storage reservoir, and the valve chamber 10 being in communication with the reservoir through passage 48, the 40 fluid pressure therein rises and equalizes around the piston heads 6 and 7. The pump pressure being less than the tension of spring 17, the release valve 18 is permitted to open and fluid in chamber 9 is vented to the atmosphere, while the valve 15 being closed, the fluid pressure which equalizes around the piston head 6 builds up the pressure in chamber 8 and operates to shift the main valve mechanism to its cut-in position, as 45 shown in Fig. 1. In this position, a cavity 50 in the main slide valve 11, connects port 21, leading to piston chamber 4, with exhaust port 51, and as piston chamber 20 is open to the atmosphere through passage 22 and ports 23, the full area of the piston 2 is now subject to atmospheric pressure. As the pump pressure increases by operation of the pump, the low pressure diaphragm first operates to close the release valve 18 and 50 when the pump pressure slightly exceeds the tension of the high pressure spring 14, the diaphragm 13 operates the release valve 15, and air is vented from piston chamber 8, through the passage 49. The main operating piston thereupon first moves the auxiliary valve 12 so that cavity 52 therein connects a port 53 in the main slide valve 11 with a port 54. Port 53 being now in register with port 43 and port 54 being connected with a port 55, leading to piston chamber 8, communication is opened from the piston chamber 8 to the blow out piston valve 42, thereby permitting fluid under pressure in chamber 8 to flow to the piston valve 42 and this fluid pressure, acting on the inner face of said piston valve, causes the same to open and vent air through the blow-out passage 44 onto the switch contacts. The movement of the main valve mechanism is thus accelerated by the venting of air to the blow-out 55 in addition to the venting of air at the release valve 15. The continued movement of the main piston causes the shifting of the main slide valve 11 and port 56 therein is brought into register with port 21. Air is 60 then admitted from the valve chamber 10 to the annular piston chamber 4, and acting on piston 2, forces the same outwardly. The movement of the main valve piston also opens communication through a groove 57 around piston head 6 from the valve chamber 10 to the chamber 8, so that fluid at main reservoir pressure can flow into chamber 8 and thence through the passage 43, past the blow-out piston valve 42, to supply a strong 65 blast of air for the blow-out for the purpose of extinguishing or preventing the formation of arcs as the switch contact members separate. As the piston 2 moves outwardly, the contact member 29 rises and is followed 70 up by the contact member 32, the latter being yieldingly pressed upwardly by the action of the spring 37, so that the contact members remain in contact until the stop 38 on the arm 33 engages with the bracket standard 34, then the contacts of course separate and break the motor circuit upon the further upward movement of the contact member 29. A little before the contact members separate, 75 the piston 2 passes over one of the port openings 23, so that a communication is established from chamber 4 to passage 22 and thence to piston chamber 20. Now the port opening of passage 21 into chamber 4 is so restricted that upon opening the port 23 to said chamber, the effect is that of opening a vent port from the chamber, as air is not supplied through the restricted port 21 fast enough to make up for the increased piston area open to fluid pressure and consequently 80 the tendency of the piston to accelerate its speed too rapidly is checked. It should be understood that the piston 2 still moves rapidly enough to prevent the formation of arcs as the switch contacts separate, but at 85

the same time an excessively rapid movement is prevented, as such movement is unnecessary and tends to cause pounding and possible breakage of parts.

5 The piston valve 42, being subject to the pressure of a spring 47, causes a corresponding back pressure in piston chamber 8, which though ordinarily of no consequence might in some cases prevent the main valve mechanism from moving as rapidly as desired and so, in order to insure a more rapid movement of the parts I may provide the piston head 6 with a differential piston head portion 58 adapted to fit snugly within a piston chamber 59. This piston chamber 59 communicates with passage 49 leading to the release valve 15, so that whenever said valve is opened, it will be seen that the pressure in chamber 59 is quickly reduced substantially to atmospheric pressure, regardless of the pressure in chamber 8, thus facilitating the rapid movement of the main valve parts. In the extreme cut-out position of the main valve piston, the piston head 6 seats on an annular ring 60, and thus leakage of air from the piston chamber 8 and the main reservoir is prevented, during the time that the parts remain in the cut-out position. In moving to the cut-out position, the piston 2 passes over the port 46, and air is admitted from the piston chamber 4 to the spring side of the piston valve 42, thus permitting the fluid pressures to equalize on opposite sides thereof. The spring 47 will then close the piston valve 42 and prevent further flow of air through the blow-out passage 44. As the pump pressure diminishes, the high tension diaphragm first permits the valve 15 to close and then when the pressure becomes 40 slightly less than the tension of the low pressure spring 17, the release valve 18 opens and air is vented from the piston chamber 9, and the main valve mechanism instantly moves to its cut-in position, connecting the annular space 4 through passage 21 and cavity 50 with exhaust port 51. The venting of air from the space 4 causes the inward movement of piston 2, and, passing over the port openings 23, the movement of the piston 2 establishes communication from the central piston chamber 20 to the atmospheric port 24. This occurs when the contact 29 has moved to within a short distance of the contact 32, say about one-fourth of an inch, 55 and thereupon, the sudden venting of air from the central piston chamber 20 causes the rapid movement of the piston, and thus the contact members of the switch are brought together with a quick, snap-like action. As the piston 2 continues its inward movement, the contact member 29 presses against the contact member 32 and moves the same inwardly against the resistance of the spring 37. The movement of each contact member about a different center is such

that the contacts at first engage at the outer end portions, as indicated in Fig. 4, and then by a relative sliding or wiping and rolling movement finally assume the cut-in position, as shown in Fig. 1, in which the portions 70 of the switch in contact are some distance back from the ends. In the cut-in position of the switch, the portion 61 of the switch arm 33 engages the stop 62 and so the pressure between the contacts at this time is 75 equal to the pressure of the springs 25 and 26 less the pressure of the spring 37, of course taking into consideration the leverage of the switch arm 28. In practice the springs are preferably made to exert a pressure of about 110 pounds and the piston stem 27 being pivoted about midway on the lever 28, the downward pressure on contact 29 is about 55 pounds. A heavy contact pressure is thus produced between the switch 80 contacts when in the cut-in position, insuring an efficient connection of good conductivity.

It will now be apparent that a pump governor constructed according to my invention 90 is adapted to effect the quick snap-like action of the switch in cutting-in and by shifting the relative place of contact of the switch contacts, a smooth, clean contact is insured, all of which tends to eliminate 95 troubles due to arcing and poor contacts. Though of special utility in connection with the use of heavy currents and low voltages, the construction may, of course, be employed generally with advantage.

Having now described my invention, what I claim as new and desire to secure by Letters Patent, is:—

1. A pressure governor comprising a controlling device, an actuating piston therefor, valve means governed by the pump pressure for supplying fluid to operate said piston, and means operated by the movement of said piston in one direction, for venting fluid from one side of the piston and by the 105 movement of said piston in the opposite direction for supplying fluid to one side of the piston.

2. A pressure governor comprising a pump controlling device, an actuating piston 115 therefor having two pressure receiving surfaces, a valve mechanism governed by the pump pressure for varying the fluid pressure on one surface, and means operated by the movement of said piston for varying the 120 pressure on the other surface.

3. A pressure governor comprising a pump controlling device, an actuating piston therefor having two pressure receiving surfaces, a valve mechanism governed by 125 the pump pressure for venting fluid from one surface, and means operated by the piston for venting fluid from the other surface to cause the sudden movement of said piston.

4. A pressure governor comprising a pump controlling device, an actuating piston therefor having two pressure receiving surfaces, a valve mechanism governed by the pump pressure for supplying fluid under pressure to one surface, and means operating upon movement of the piston for venting fluid from one surface to the other to regulate the movement of said piston.
- 10 5. A pressure governor comprising a controlling switch, an actuating piston therefor, a main valve and an abutment for controlling the fluid pressure on said actuating piston, a blow-out valve means operated by fluid pressure, and an auxiliary valve having a movement relative to said main valve and operated by the preliminary movement of said abutment for venting fluid under pressure from one face of said abutment to said blow-out valve means to operate the same.
- 15 6. A pressure governor comprising a controlling switch, an actuating piston therefor, valve means and an abutment having two piston heads for controlling the fluid pressure on said actuating piston, a release valve device governed by the pump pressure for venting fluid from one piston head, a blow-out valve means for the switch, and means operated by the movement of said abutment for supplying air from the
- 20 other piston head to said blow-out valve means.
7. A pressure governor comprising a controlling switch, an actuating piston therefor, a main valve and an abutment having two piston heads for controlling the fluid pressure for operating said actuating piston, a release valve device governed by pump pressure for venting fluid from one piston head, a blow-out valve means for the switch, and an auxiliary valve having a movement relative to the main valve and operated upon preliminary movement of said abutment for venting fluid from the other piston head to operate blow-out valve means.
- 25 8. A pressure governor for pumps comprising a pump controlling switch, an actuating piston therefor, a valve mechanism for controlling the fluid pressure on said actuating piston, means subject to pump pressure for venting fluid from said valve mechanism, and a blow-out valve means operated by fluid vented from said valve mechanism for supplying air to said switch.

In testimony whereof I have hereunto set my hand,

WALTER V. TURNER.
